VISIBLE INDEX UNIT

Rudolph Janovsky, Berwyn, and Saul Hurtig,
Chicago, Ill.

Application June 19, 1951, Serial No. 232,328

1 Claim. (Cl. 129-16)

1

Our invention relates to index files as contained in ring binders, file folders, catalog binders and cabinets, and particularly to the type involving record sheets or cards mounted in cascading order, and one object is to provide a unit designed to support the record sheets to the best advantage.

A further object is to employ a series of anchoring devices for the record sheets in respect to a supporting sheet included in the novel unit, such anchoring devices being manually applicable to mount or remove the record sheets with facility.

Another object is to construct the index unit with a self-contained support formed in a manner to permit groups of record sheets to be secured in place in succession as they are supplied or needed, and to be removable at any point in the series.

An additional object is to employ a securing device for the record sheets which enables them to be anchored to each other throughout the series and secured to the supporting sheet of the unit only at desired points.

An important object is to design the novel unit along lines of extreme simplicity, in order to make its production economical and its use or handling easy for the average person.

With the above objects in view, and any others which may suggest themselves from the description to follow, a better understanding of the invention may be had by reference to the accompanying drawings, in which—

Fig. 1 is a perspective view of a typical ring binder, showing the application of the novel unit;

Fig. 2 is an elevation showing the manner of mounting a series of record sheets in the unit;

Fig. 3 is an enlarged view of the upper portion of Fig. 2 from the right-hand side;

Fig. 4 is a top plan view of the showing in Fig. 2 on an enlarged scale and indicating a record sheet secured to the unit;

Fig. 4a is a similar view showing a pair of record sheets secured to each other and not to the unit;

Fig. 5 is a perspective view showing two modifications of the contents for the unit; and

Fig. 6 is a perspective view of an anchoring device.

The mounting of record sheets often occurs in ring binders, and the novel index unit is designed to facilitate such mounting. For this purpose, the basic element of the unit is preferably a card indicated in the drawings at 10, such card having

2

the characteristics of a binder leaf, such as the cloth hinge 11 and ring perforations 12.

In order to form the index unit, the base card 10 receives a vertical sheet 15 of thin cardboard, such sheet being secured to the base card 10 by a suitable adhesive. The sheet 15 has a pair of side wings 16 which are bent on folding lines 17 to project at an angle from the base card 10. The wings 16 are reinforced by being tucked between a fold 18 of cellophane or a similar tough material, whereby to stiffen the wings; and the reinforcing wings are cut with a vertical series of perforations 20.

The sheet 15 is designed to serve as a support for a series of record sheets 22 as shown in Figs. 1 and 3, these being arranged in downwardly cascading order to present visible index portions; and for the purpose of securing their support from the sheet 15, the record sheets are formed with pairs of perforations 25 spaced laterally and vertically as the supporting sheet perforations 18.

Means for anchoring the record sheets 22 to each other and to the supporting sheet 15 involve a strip 30 of fibre, the end portions of the strip being reduced in width to form tongues 31 which are pointed terminally at 32, a clear illustration of such a strip occurring in Fig. 6. The upper right-hand portion of Fig. 1 shows a single anchoring strip near the top secured with its tongues 31 passing through the wings 16 of the supporting sheet 15. Two anchoring strips are shown in succession a short distance below the illustration just referred to, and mounted in the same manner; and it will be noted that the width of the strips 30 is such that they abut along the contiguous edges when mounted in succeeding pairs of perforations 25 of the supporting sheet 15. This arrangement reinforces the strips against angular deviation, and lends them a smooth surface as a group.

The lower portion of Fig. 2 shows that a single record sheet is secured to the supporting sheet 15 by the application of an anchoring strip 30, first through the perforations 25 of the sheet 22, and then through the perforations 20 of the supporting sheet 15. It is noted that the lower pair of perforations 25 have been employed for the purpose just stated. Therefore, if the next record sheet 22 is to be mounted in upward order over the previous one, its anchoring strip 30 is made to pass through the upper pair of perforations 25 in the previous sheet before passing through the similarly located perforations of the supporting sheet 15. The second record sheet is thus secured not only to the supporting sheet but also

to the first record sheet by the above operation; and the second advantage occurs in the stacking of the second anchoring strip 13 upon the first one for additional support.

Fig. 4 shows the manner in which the tongues 31 of the anchoring strip 30 pass through the record sheet and supporting sheet to a position in front of the base card 10. The backing function of the base card in respect to the tongues 31 prevents them from receding or creeping to loosen their anchoring hold, and the strips may therefore be considered as locked in place to hold the record sheets 22 securely against vibrations or shocks suffered by the unit.

Fig. 4a shows the manner of anchoring the record sheets to each other, and not to the supporting sheet 15. In this case, it is expedient to procure such anchoring for the top and bottom record sheets in order to retain the series to the unit. This type of mounting is visible where the record sheets are light and designed for frequent removal, since it is easier to withdraw the anchoring strips where they pass through only the record sheets. However, such withdrawal is not difficult in case more or all of the record sheets are secured through the supporting sheet 15. The simple application of the invention is shown in Fig. 1, involving a base of record sheet mounted on the unitary base card 10. A modified mounting is shown in the right-hand portion of Fig. 5, where the back cover 35 of a folder or blank book is employed as the base card. Where the record sheets are wide, as indicated in the modified showing, it is preferable to use two rows of anchoring devices, as indicated at 36 and 37.

A further modification of the invention is indicated in the left-hand portion of Fig. 5, where a cover 40 of a blank book serves the function of the base card 10. Here, the record sheets are replaced by a set of pockets 41 adapted to carry food subject cards 42, the pockets having cut-out portions 43 to disclose the indexing portions of the cards. Thus, a card index may be provided for the home to incorporate food information or recipes, with the pockets and cards changeable at will.

It will now be apparent that the novel index unit makes it possible to group many record sheets, cards, card pockets, or other indexing elements in compact form for easy identification and securely anchored to a backing unit forming a part of a loose leaf binder or blank book. Further, means are provided to securely anchor the index elements to each other and to their unitary support in any desired order, and to make such elements removable or interchangeable with ease. Further, the anchoring device employed in the unit is simple, compact, and self-locking, so that the material supported in the binder or

blank book may be relied upon to hold its place as arranged or mounted in case of vibration or shock. Finally, the novel index unit is composed of few parts which may be fabricated by modern machine methods on an economical basis and for easy handling by the average person.

While we have described the invention and its modifications along specific lines, various minor changes or refinements may be made therein without departing from the principle thereof, and we reserve the right to employ all such changes and refinements as may come within the scope and spirit of the appended claims.

We claim:

A visible index unit comprising a base member, a retainer member comprising a central body portion rigidly secured to said base member, and a pair of oppositely disposed laterally extending wings foldable upwardly relative to said base member, each of said wings being provided with a series of perforations, each perforation in one wing being aligned laterally with a corresponding perforation in said other wing, a series of sheets, each of said sheets being provided with two vertically spaced pairs of perforations adapted to register with two adjacent pairs of perforations in said wings, and a pair of fastening members each having a body portion and a pair of end portions, one of said fastening members having its body portion overlying the portion of one of said sheets between the lower pair of perforations and having its end portions extending through said lower pair of perforations and through perforations in the preceding sheet and said wings aligned therewith, said other fastening member having its body portion overlying the portion of said first mentioned sheet between the upper pair of perforations and having its end portions extending through said upper pair of perforations and through perforations in said wings aligned therewith, whereby each of said sheets is secured to said wings at a plurality of vertically spaced positions.

RUDOLPH JANOVSKY.
